ROTARY PRINTING-PRESS.

1,137,859.

Specification of Letters Patent.

Patented May 4, 1915.

Application filed April 24, 1913. Serial No. 763,214.

To all whom it may concern:

Be it known that I, WILLIS K. HODGMAN, a citizen of the United States, and a resident of Taunton, in the county of Bristol, 5 and State of Massachusetts, have invented an Improvement in Rotary Printing Presses, of which the following description, in connection with the accompanying drawings, is a specification, like characters on the drawings representing like parts.

This invention relates to rotary printing presses.

In order that the principle thereof may be readily understood, I have disposed a single embodiment thereof in the accompanying drawings, wherein—

Figure 1 is a longitudinal vertical section of a rotary printing press embodying my invention; Fig. 2 is a side elevation showing 20 the gearing preferably employed for driving the cylinders; and Fig. 3 is a longitudinal section upon the line 3—3 of Fig. 2.

One of the primary objects of the invention is the provision of a rotary printing 25 press which will print at least one, and preferably more than one, sheet at each revolution of the impression cylinder and will deliver the printed sheets directly from the impression cylinder printed side up.

Another object is to provide a printing 30 press in which the delivery mechanism shall be located above the feeding mechanism and on the same side of the impression cylinder.

If desired, my invention may be embodied 35 in a rotary printing press of that type wherein an impression cylinder is provided, and which heretofore has required a single revolution for each printing operation. In accordance with the preferred embodiment 40 of my invention I, in such case, provide the impression cylinder with a plurality of impression surfaces so that a plurality of sheets are printed at each revolution of said impression cylinder.

In accomplishing the objects of my invention and in accordance with the preferred embodiment thereof, I increase the diameter of the impression cylinder and equip it with a plurality of impression surfaces, each of 50 which is adapted to print in turn from the same-form or design.

Referring more particularly to the draw-

ings wherein I have represented one embodiment of my invention, the impression cylinder is represented at 1. It is here shown as 55 equipped with two impression surfaces 2, 3, but obviously within the scope of my invention one, or any suitable greater number of impression surfaces may be provided. These impression surfaces are primarily intended to print in turn from the same form or design, and each of them is provided with the usual grippers 4, which in turn receive the sheets from the grippers of the feeding cylinder.

I have represented my invention as applied to a two-color offset press, wherein the printing plates are preferably of sheet metal, such as aluminum, and are carried by suitable printing cylinders 5, 6, which are equipped with the necessary damping mechanism, 7, and inking mechanism 8. Obviously, any suitable type of printing or equivalent cylinders or devices and associated mechanism may be provided. I have represented the 75 printing cylinders as having associated therewith a corresponding number of offset cylinders 9, 10, preferably provided with suitable rubber blankets, which in turn print upon every sheet as presented to them by the 80 impression cylinder 1. The construction and arrangement of parts is such that each offset or printing cylinder in turn registers with every impression surface of the impression cylinder. As herein shown, each offset or 85 printing cylinder is provided with at least one printing surface arranged to register with every impression surface of the impression cylinder during each revolution of the impression cylinder.

While I have illustrated my invention as embodied in a two color, offset press, it will be readily understood that by removing the offset cylinders and moving the printing cylinders into contact with the impression cylinder, a printing press is obtained wherein the printing takes place direct from the printing cylinders, and that such modified form of press is within the scope of my invention. Obviously the invention is applicable to a single color press and also one adapted to print two or more colors.

The feeding cylinder 11, its feed board 12 and its single set of grippers 13 are

cated that said cylinder delivers the sheets to the grippers of the impression cylinder 1 near the lower side of the latter and at what I will for convenience term the rear 5 of the press.

Inasmuch as an important object of my invention is to produce a press that will print one or more colors, according to whether it be a single or multi-color press, 10 from the same form or forms, upon every sheet in perfect register with the sheet, and so that the subsequent colors or printings may register with the previous printings and the sheet, it is of great importance that 15 every sheet be treated as nearly alike as possible. Therefore, I provide a single instrumentality or set of instrumentalities for taking every sheet from the feed board or sheet feeding machine. To that end, I have 20 herein disclosed a single set of grippers upon the feeding cylinder, whereby each and every sheet is taken by said set of grippers from the feed board and presented to the impression cylinder.

25 Any suitable delivery mechanism may be employed. In the present embodiment of the invention, I have represented delivery tapes 14 and co-acting strippers 15 positioned above the feeding cylinder 11, and at 30 the same side of the press as the feeding cylinder, whereby the printed sheets are delivered above the feeding cylinder and to the rear of the press printed side up, so that the freshly printed matter does not 35 come in contact with any object. Owing to the described increase in the diameter of the impression cylinder 1, there is provided sufficient room between the feed board 12 and the delivery tapes 14 for feeding the 40 sheets to the feeding cylinder.

While the invention is particularly adapted to presses wherein the impression is taken by means of a rubber blanket not requiring any make-ready, it can be used in a letter 45 press by making ready the two or more impression surfaces in the usual manner.

I have represented the feeding cylinder 11, the impression cylinder 1 and the offset cylinders 9, 10 as mounted in eccentric bearings 16, so that the cylinders may be separated through the action of mechanism, not shown, in the usual manner, when it is desired to have them not contact with each 50 other. The feeding cylinder and the impression cylinder, however, are never separated, but move together, the described separation being necessary only between the impression cylinder 1 and the offset cylinders 9 and 10, and the said offset cylinders and the 55 printing cylinders 5, 6.

I have represented the feeding cylinder and the offset cylinders as each equipped with split gears 17, 18, and the printing cylinders as equipped with the corresponding 60 circumferentially adjustable gears 19. The

said gears are circumferentially movable relative to each other and to the cylinders in order that the cylinders may be moved relatively to each other to obtain registry, and the gears may be moved to take up any 70 back-lash or looseness in the gearing.

It will be evident from the foregoing description that I have provided a rotary printing press wherein two or more sheets may be printed at each revolution of the 75 impression cylinder or wherein a single sheet may be printed at each revolution thereof, and that the printed sheets are delivered printed side up at the same side of the press as the feeding mechanism. It will 80 be understood that in the preferred embodiment of the invention the surface speed is not increased. The offset cylinders 9, 10 determine the surface speed, and hence the impression cylinder 1 is rotated at a sufficiently slower speed than heretofore to compensate for its increased diameter.

Having thus described one illustrative embodiment of my invention, I desire it to be understood that although specific terms are employed, they are used in a generic and descriptive sense and not for purposes of limitation, the scope of the invention being 85 set forth in the following claims.

Claims.

1. A rotary printing press comprising in combination, an impression cylinder provided with a plurality of impression surfaces; a coöperating feeding cylinder at the rear of the press and contacting with the lower portion of said impression cylinder, said parts being constructed and arranged to effect the feeding of a sheet to each impression surface during a single revolution of the impression cylinder, said feeding cylinder having a single set of grippers for all the sheets; a coöperating delivery mechanism at the rear of the press to receive sheets printed-side-up from the top of said impression cylinder; and one or more offset or 100 printing cylinders each provided with a printing surface arranged to coöperate with the said impression cylinder and each said surface thereof in turn to register with every impression surface of said impression cylinder during each revolution of said impression cylinder.

2. A rotary printing press comprising in combination, an impression cylinder provided with a plurality of impression surfaces; a coöperating feeding cylinder at one side of the press, said parts being constructed and arranged to effect the feeding of a sheet to each impression surface during a single revolution of the impression cylinder, said feeding cylinder having a single set of grippers for all the sheets; printed sheet delivery mechanism at the same side of the press and positioned above said feeding cylinder; and one or more offset or 115 120 125 130

printing cylinders each provided with a printing surface arranged to coöperate with said impression cylinder and each said surface thereof in turn to register with every impression surface of said impression cylinder during each revolution of said impression cylinder.

3. A rotary printing press comprising in combination, an impression cylinder provided with a plurality of impression surfaces; a coöperating feeding cylinder at the rear of the press and contacting with the lower portion of said impression cylinder, said parts being constructed and arranged to effect the feeding of a sheet to each impression surface during a single revolution of the impression cylinder, said feeding cylinder having a single set of grippers for all the sheets, delivery tapes at the rear of the press and coöperating with the upper portion of said impression cylinder; and one or more offset or printing cylinders each provided with a printing surface arranged to coöperate with the said impression cylinder and each said surface thereof in turn to register with every impression surface of said impression cylinder during each revolution of said impression cylinder.

4. A rotary printing press, comprising in combination, an impression cylinder provided with a plurality of impression surfaces; a feeding cylinder, said parts being constructed and arranged to effect the feeding of a sheet to each impression surface during a single revolution of the impression cylinder, said feeding cylinder having a single set of grippers for all the sheets, and a coöperating feed board, and delivery mechanism at the same side of the press as the feeding cylinder and positioned thereabove; and one or more offset or printing cylinders each provided with a printing surface arranged to coöperate with the said impression cylinder and each said surface thereof in turn to register with every impression surface of said impression cylinder during each revolution of said impression cylinder.

5. A rotary printing press comprising in combination, an impression cylinder provided with a plurality of impression surfaces; a feeding cylinder, said parts being constructed and arranged to effect the feeding of a sheet to each impression surface during a single revolution of the impression cylinder, said feeding cylinder having a single set of grippers for all the sheets, delivery mechanism at the same side of the press as the feeding cylinder and positioned thereabove, and adapted to receive sheets from the impression cylinder printed-side-up; and one or more offset or printing cylinders each provided with a printing surface arranged to coöperate with the said impression cylinder and each said surface

thereof in turn to register with every impression surface of said impression cylinder during each revolution of said impression cylinder.

6. A rotary printing press comprising in combination, an impression cylinder provided with a plurality of impression surfaces; feeding mechanism, said parts being constructed and arranged to effect the feeding of a sheet to each impression surface during a single revolution of the impression cylinder, said feeding mechanism being provided with a single set of feeding instrumentalities for all sheets, delivery mechanism at the same side of the press as said feeding mechanism, the latter being adapted to receive sheets from the impression cylinder printed-side-up; and one or more offset or printing cylinders each provided with a printing surface arranged to coöperate with the said impression cylinder and each said surface thereof in turn to register with every impression surface of said impression cylinder during each revolution of said impression cylinder.

7. A rotary offset printing press comprising in combination, an impression cylinder provided with a plurality of impression surfaces; a feeding cylinder at the rear of the press and contacting with the lower portion of said impression cylinder, said parts being constructed and arranged to effect the feeding of a sheet to each impression surface during a single revolution of the impression cylinder, said feeding cylinder having a single set of grippers for all the sheets; a delivery mechanism at the rear of the press to receive sheets printed-side-up from the top of said impression cylinder; one or more printing cylinders at the front of the press; and an offset cylinder coöperating with each printing cylinder each offset cylinder being provided with a printing surface arranged to coöperate with the said impression cylinder and each said printing surface thereof registering with every impression surface of the said impression cylinder during each revolution of said impression cylinder.

8. A rotary two color offset printing press comprising in combination, an impression cylinder provided with a plurality of impression surfaces; a feeding cylinder at the rear of the press and contacting with the lower portion of said impression cylinder, said parts being constructed and arranged to effect the feeding of a sheet to each impression surface during a single revolution of the impression cylinder, said feeding cylinder having a single set of grippers for all the sheets; a delivery mechanism at the rear of the press to receive sheets printed-side-up from the top of said impression cylinder; two printing cylinders at the front of the press; and provided with a printing surface arranged to coöperate with two offset cylin-

ders each coöperating with its printing cylinder and each said printing surface thereof the said impression cylinder and registering with every impression surface of the said 5 impression cylinder during each revolution of said impression cylinder.

In testimony whereof, I have signed my

name to this specification, in the presence of two subscribing witnesses.
